UNITED STATES PATENT OFFICE

HOWARD H. LANNING, OF TOPEKA, KANSAS

FIRE DOOR

Application filed July 3, 1929. Serial No. 375,809.

My invention is especially adapted to fire doors for locomotives and relates more particularly to the fire door rings of locomotives; although adaptation of the invention 5 to other types of boiler fire doors is apparent.

The invention has for its object the provision of a construction whereby air may be admitted to the firebox without the necessity of opening the fire door and therefore without the danger encountered with constructions as at present employed.

A further object of the invention is to provide regulable means whereby the air may be admitted in the desired and correct 15 amounts to aid combustion and consequently reduce the smoke emitted from the stack.

Another object of my invention is to provide air admitting means arranged so that in the event of a fire box or flue explosion, the 20 force of such explosion will be conveyed to and discharged at a point removed from the operating positions of the enginemen.

The objects and advantages of my invention will be readily comprehended from the 25 detailed description of the accompanying drawings, wherein—

Figure 1 is an elevation of the rear of a coal burning type of locomotive fire box, portions being broken away, illustrating the application of my invention.

Figure 2 is a vertical sectional view taken substantially on the line 2—2 of Figure 1, with the fire door omitted.

Figure 3 is a sectional elevation taken substantially on the line 3—3 of Figure 2 looking in the direction of the arrows.

Figure 4 is a vertical sectional elevation of the lower end of the mechanism as disclosed in Figure 2, illustrating the air admitting 40 means in open position.

In the drawings, I have illustrated my invention applied to a coal burning locomotive and for purposes of exemplification have shown the invention applied to what is 45 known as the "Franklin butter-fly" type of

pneumatic fire door; namely a fire door which is adapted to be swung through a vertically disposed arc and which is usually operated by pneumatic means attached to the boiler back head, but which means is omitted as it 50 forms no part of my invention.

The rear water leg of the boiler is shown at 10 in Figure 2 formed by the inner sheet 11 and outer sheet 12 which are provided with the usual fire door flanges as at 13 about 55 the fire box opening.

My invention involves a hollow or chambered fire door ring 14 disposed about the fire door opening in the boiler head and which ring involves the downwardly extending portion 15 which also encircles the sides of the fire door ring proper and provides an air conduit or conveying channel 16 which extends preferably beneath the firing deck or floor 17 of the cab of the locomotive.

The ring is provided, in this particular instance with the "Franklin butter-fly" type of pneumatic door which is located at 18 and arranged to rotate on the studs 19 supported by the bosses 20, while the bottom of the fire door is held in position against the opening in the ring by the lugs 21, 21 which are formed integral with the fire door ring.

The fire door ring, as is apparent, conforms with the contour or shape of the back head 75 of the fire box and is chambered throughout; with the back head, in the specific exemplification, constituting the rear wall of the air chamber in the ring. The air chamber extends about and communicates with the fire door opening in the ring, except for the trans-

verse apertured boss portions 22 and 23 which receive the studs 24 and 25 whereby the ring 14 is securely fastened to the boiler back head 12. The ring is of proper thickness so as to 80 provide a suitable air chamber or conduit and has its perimeter 26 formed to extend substantially flush with the boiler back head 12.

The ring, on its perimeter and at opposite sides, is also provided with flanges or lobes 90

as at 27 to receive the studs 24 for firmly securing the fire door ring in place.

The ring 14 is provided with a shovel shield 28 formed, preferably, integral therewith and 5 made arcuate or dished to conform with the lower part of the fire door opening as shown. The shield 28 extends into the fire door opening and preferably in slight spaced relation with the door opening flange 13 of the boiler 10 back head, as shown in Figure 2.

The fire door ring 14, as previously described, is formed so that air is drawn into the fire door opening past the door opening flange 13, at all points, a small amount of 15 air being also allowed to pass beneath the shield 28 through the opening or space indicated at 29 in Figure 2.

By arranging the shovel shield as described and by permitting air to pass around the bottom face of the shield, the fire box door opening flange 13 and the shovel shield 28 are 20 protected and overheating of said parts is prevented.

The bottom of the air chamber or conduit 25 16 is provided with a damper 30 which extends throughout the bottom of the air conveying portion of the ring 14 and constitutes a closure for the air admitting end of the conduit or air chamber formed within the 30 shell constituting the fire door ring 14.

The damper 30, which constitutes the bottom of the chamber formed by the fire ring shell, is shown provided with upstanding apertured lugs or ears 31.

35 These lugs or ears are disposed between the lugs or ears 32 arranged in pairs at the bottom of the fire door ring shell and which are likewise apertured to receive the hinge pins 33, see Figure 1, which latter may be secured in 40 place in any suitable manner, as for example by cotters as at 34. The lugs or ears 31 on the damper 30 are formed to permit the damper 30 to swing downwardly into open position, as shown in Figure 4.

45 One end of the damper 30 is provided with an arm or extension 35 shown terminating in an upwardly disposed bifurcated portion 36; the bifurcations being apertured to receive a suitable pin 37 for pivotally connecting a 50 lever 38 thereto. Lever 38 is provided with a longitudinally disposed slot 39 which receives a stud 40 threaded into a lug 41 formed integral or secured to the fire door ring or shell 14; the stud being held against rotation in any 55 suitable manner as for example by a nut 42. The outer end of the stud 40 is provided with a small lever or clamp member 43 which is adapted to clamp the lever 38 in the desired position against the side of the lug 41. From 60 this construction it is apparent that when the small lever or clamp member 43 is turned out of clamping relation with the damper control lever 38, the latter may be moved downwardly or upwardly, as the case may be, and thereby either open or close the damper 30

to the desired position or extent of opening. The position of the lever and therefore also of the damper are maintained by again screwing clamp member 43 into clamping relation with the side of damper operating lever 38. 70

As is evident from the construction shown and described, the desired amount of air for aiding combustion in the fire box may be controlled by the enginemen or operator by simply releasing clamp member 43 and forcing lever 38 downwardly a distance sufficiently to open damper 30 to the desired extent. The air entering the chamber or conduit 16 passes upwardly throughout the entire chambered fire door ring 14 and enters the fire door opening into the fire box at all points because the air chamber extends completely about all sides of the opening; while some of the air will pass through the space or opening 29 beneath the shovel shield 28. 80 The air passing intermediate of the shovel shield and the fire door opening flange 13 protects the flange as well as the shield against overheating. 85

With the fire door ring extending to a point beneath the firing deck or floor 17 of the cab, it is apparent that in the event of fire box or flue explosions occurring, the force of such explosions will pass out and downwardly through the conduit or air chamber and 90 through the opening made by the open damper and therefore be discharged at a point below the firing deck, thus protecting the engine-crew from injury and the dangers at present encountered because the usual fire door ring heretofore employed does not provide such relief. 95 With constructions as heretofore employed, explosions of the type mentioned have frequently blown the rings and doors loose from the fastening which has resulted in loss 100 of life or serious injury to the engine-crew in the cab of the locomotive. 105

The draft of the locomotive causes air to be drawn upwardly through the air chamber 16 without the necessity of having the fire door open into the cab as is the present practice. Furthermore, with my improved construction air in correct amounts or proper quantity may be admitted to aid the combustion and thus also to reduce the smoke 110 emitted at the stack of the locomotive; and when the damper has been adjusted or opened to the desired degree, it may be set at such adjusted position by simply screwing clamp member or lever 43 into clamping 115 relation with the damper control lever 38. 120

As previously stated, I have, for purpose of exemplification, shown my invention applied to a locomotive firebox having what is known as the Franklin butter-fly type of 125 pneumatic door, but it is apparent that the invention is applicable to other types with but slight variations in contour to suit the type of fire box; and while the exemplification is believed to be the best adaptation of 130

the invention, described in terms employed merely as terms of description and not as terms of limitation, modifications may be made without, however, departing from the 5 spirit of my invention.

What I claim is:

1. A fire box provided with a fire door opening, a hollow ring disposed about said opening and secured to the fire box, said ring 10 providing an air chamber about all sides of the opening and entirely open to said opening, an air conducting extension secured to the lower side of said ring and leading to a point beneath the firing deck of the fire box 15 and open at the bottom, a pivotally mounted closure member for the open bottom of said extension; and a reciprocatingly mounted lever for controlling said closure member.
2. In combination with a locomotive fire 20 box having a fire door opening, chambered means secured to the firebox about said opening with the chamber arranged in communication with all sides of the opening, said means having an air admitting portion extending downwardly along the rear wall of 25 the fire-box to a point beneath the firing deck of the locomotive and being open at the bottom, a damper hingedly secured to said portion for controlling said open end, and a reciprocatingly mounted lever operable from 30 the firing deck whereby said damper may be controlled and locked in adjusted positions.
3. A fire box provided with a fire door 35 opening, a hollow open sided member secured with its open side to the rear wall of the fire box and disposed entirely about said opening and communicating with all sides of said opening, said member having an air admitting portion extending downwardly beneath 40 the firing deck of the fire box and having an air inlet at the bottom, a movable closure member for said inlet, means whereby the member may be controlled and the amount of admitted air regulated, and a shovel shield 45 secured to said member so as to extend into the fire door opening in spaced relation with the fire box walls at the bottom of said opening.
4. A fire box provided with a fire door 50 opening, a hollow open sided ring secured entirely about said opening to provide an air chamber in communication with all sides of the fire-door opening in the fire-box, said ring having side walls adapted to fit against 55 the rear wall of the fire-box to provide the air chamber about the opening, studs extending rearwardly from the front wall of the ring adapted to receive fastening bolts for securing the ring to the fire-box, a portion integral with the bottom of said ring and arranged to extend beneath the firing deck of 60 the fire box to provide an air admitting channel communicating with the bottom and sides of the ring, said depending portion being 65 open at its bottom, a damper pivotally se-

cured to said ring for controlling said open bottom; an operating lever slidably secured to said portion and operatively connected with said damper, means for locking said lever with the damper in adjusted positions, 70 and a shovel shield integral with said ring and disposed inwardly into the fire-door opening in spaced relation with the fire-box wall to provide an air space therebetween.
